UNITED STATES PATENT OFFICE.

ROBERT NEWELL, OF PHILADELPHIA, PENNSYLVANIA.

FRAME FOR CARDS.

SPECIFICATION forming part of Letters Patent No. 240,751, dated April 26, 1881.

Application filed August 20, 1880. (Model.)

To all whom it may concern:

Be it known that I, ROBERT NEWELL, a citizen of the United States, residing in the city and county of Philadelphia, and State of Pennsylvania, have invented a new and useful Improvement in Frames for Cards, which improvement is fully set forth in the following specification and accompanying drawings, in which—

10 Figure 1 is a face view of a framed placard or business-card embodying my invention. Fig. 2 is a section thereof in line $\alpha\alpha$, Fig. 1. Fig. 3 is a rear view thereof, partly taken away. Fig. 4 is a face view of a modification.

15 Similar letters of reference indicate corresponding parts in the several figures.

My invention consists in forming an imitation frame and affixing it to a coincident backing, whereby, when a placard is applied to said 20 backing, I produce framed placards which are light, thin, and inexpensive, and may be multiplied in great numbers, and conveniently handled, packed, and transported.

It also consists in forming the backing of two 25 or more connected pieces of wood, the grain of one piece extending at an angle to that of the other piece, and suitable strengthening strips or boards, so that the backing is strong and reliable and preserved from warping or cracking.

Referring to the drawings, A represents a business-card or similar print, having an imitation frame, A'.

B represents a solid support or backing, to 35 which the print is gummed or equivalently affixed, the edges of the backing coinciding with those of the imitation frame A'.

In practice I print on paper or suitable material, by lithography, photography, or other 40 means, an imitation frame, and affix the same to the backing B. As the print may be dupli-

cated or multiplied in great quantities, imitation frames may always be on hand. The placards are pasted or otherwise affixed to the backings, and located thereon so as to be surrounded by the imitation frames A'. A coating of sizing or varnish is then applied to the placards and frames, and thus the articles are ready for the market.

It will be seen that framed placards may be 50 quickly produced in a simple and inexpensive manner and are strong and durable. Furthermore, I obviate glass and separate frame, and produce articles that pack flat and close together, are not liable to breakage, may be readily handled, and are light in weight.

The backing B is constructed of two pieces, b b', of wood, which are placed together face to face or back to back, with the grain of one piece running at a right angle to that of the 60 other piece, and then glued, cemented, pasted, or nailed together. Strips or boards C are nailed or glued to one face of the backing, and it will be seen that the backing is a light but strong structure, and does not warp, crack, or 65 split, the strips or boards C acting as re-enforces and insuring the durability and reliability of the backing.

Having thus described my invention, what I claim as new, and desire to secure by Letters 70 Patent, is—

The method of framing business-cards or placards, consisting in forming an imitation frame by printing, then gumming or pasting the same to a coincident backing, and afterward gumming or pasting the placards to said backing, within the imitation frame, substantially as and for the purpose set forth.

ROBT. NEWELL.
